(57) **CLAIM**

The ornamental design for a ceiling fan, as shown and described.

DESCRIPTION

FIG. 1 is a top perspective view of a ceiling fan having five-way rotational symmetry showing my new design; FIG. 2 is a bottom perspective view thereof; and, FIG. 3 is a side elevational view thereof. The broken lines are for illustrative purposes only and form no part of the claimed.

1 Claim, 3 Drawing Sheets

FIG. 1

FIG. 2

FIG. 3
